UNITED STATES PATENT OFFICE

100,573

DESIGN FOR A WASHING MACHINE TUB

John J. McCabe, Euclid, Ohio

Application October 22, 1935, Serial No. 59,159

Term of patent 14 years

To all whom it may concern:

Be it known that I, John J. McCabe, a citizen of the United States of America and a resident of Euclid, in the county of Cuyahoga and State of Ohio, have invented a new, original, and ornamental Design for a Washing Machine Tub, of which the following is a specification, reference being had to the accompanying drawing, forming part thereof.

Figure 1 of the drawing is a perspective view of my design. Figure 2 is a sectional view taken on line 2—2 of Figure 1.

The tub is cylindrical in contour with an inwardly tapering top portion and it is of integral construction. The invention is characterized by

the provision in a tub of the type described, of a working opening at the top of the tub which is defined by a substantially flat annular ledge terminating at one edge in an annular stepped beaded portion which defines the tub opening and terminating at its opposite edge in a stepped beaded portion which connects the ledge to the inwardly tapering top portion of the tub.

I claim:

The ornamental design for a washing machine tub, substantially as shown and described.

In witness whereof, I have hereunto set my hand this 18th day of October, 1935.

JOHN J. McCABE.
